UNITED STATES PATENT OFFICE.

JAMES ADAIR, OF LEET, PENNSYLVANIA.

PEN-RACK.

SPECIFICATION forming part of Letters Patent No. 642,277, dated January 30, 1900.

Application filed June 13, 1899. Serial No. 720,376. (No model.)

To all whom it may concern.

Be it known that I, JAMES ADAIR, a citizen of the United States, residing at Leet township, in the county of Allegheny and State of Pennsylvania, have invented or discovered certain new and useful Improvements in Pen-Racks, of which improvements the following is a specification.

The invention described herein relates to certain improvements in pen-racks, and has for its object the detachable securing of the clamping fingers or coils to a base and the holding of the coils or fingers in proper relation to each other and as against any rocking movement on the base.

The invention is hereinafter more fully described and claimed.

In the accompanying drawings, forming a part of this specification, Figure 1 is a top plan view of my improved pen-rack. Fig. 2 is a sectional elevation, and Fig. 3 an end elevation, of the same. Fig. 4 is a longitudinal section, and Fig. 5 a transverse sectional elevation, illustrating a modified construction of the base. Fig. 6 is a sectional elevation, and Fig. 7 is an end elevation, of a modification in the manner of connecting the fingers to the clamping-bar. Figs. 8 and 9 are views similar to Figs. 6 and 7, illustrating a modification of the structure shown in said figures; and Fig. 10 is a sectional elevation of the fingers and clamping-bar, illustrating a further modification.

In the practice of my invention the base 1 is formed of any suitable material, preferably of glass. In the top of the base is formed a V-shaped groove 2, forming a seat for the fingers 3, which are formed of a series of spiral wire coils. These fingers are held in the seat 4 in the base by a clamping-bar 4, passing through the coils forming the fingers. The ends of this bar are constructed in a suitable manner to be detachably secured to the base—as, for example, by forming hooks 5 on such projecting ends, said hooks being adapted to engage recesses 6, formed in the ends of the block or base. In order that the clamping-bar may have a firm grip on the block and may be easily detached without distortion of the bar or hook, the bar is made of resilient material, so as to readily yield or bend, and the resilient or spring action of the hook may

be increased by bending eyes 9 at the points of junction of the hooks with the bar.

In order to effect a separation of the fingers 55 or their uniform distribution along the base or block, a series of two or more transverse ribs 7 are formed on the sides of the V-shaped groove 2 in the top of the base or block. These ribs may be formed, as shown in Figs. 1, 2, and 60 3, on the surfaces of the walls of the groove 2 or by cutting away or depressing the walls of the longitudinal groove, as shown in Figs. 4 and 5. Two of these ribs are so located adjacent to the ends of the blocks as to project between the first and second fingers at each end of the series, thereby properly spreading or separating the fingers. One or more intermediate ribs engage or project between intermediate fingers to limit the lateral movement of 70 the fingers when an article is placed between them. This limitation of movement is desirable, as when only the ends are held and an article is placed in the rack the intermediate fingers will yield to such an extent that the 75 article will not be firmly gripped. By the employment of the intermediate ribs principally the fingers between two ribs will yield when an article is placed in the rack. In some cases one or two intermediate ribs will effect 80 a sufficient limitation of lateral movement of the fingers; but a greater number of ribs may be employed, and in some cases it may be desirable to provide a lateral brace or stiffener for each finger, as shown in Fig. 4. 85

In order to prevent an axial movement of the fingers or coils, balls or heads 8 are formed on the ends of the coils, as shown in Figs. 1 to 5, said enlargements being sufficiently large to prevent their passage under or through the 90 clamping-bar.

In order to provide a convenient means for withdrawing the hooks 5 from the recesses 6, a handle or flap 11 may be attached to the hooks in any desirable manner—as, for example, by means of a sleeve 10, formed integral with the flap or handle and surrounding the hook, as shown in Figs. 6 and 8.

As shown in Figs. 5 to 10, inclusive, the extension of the coil or the separation of the 100 fingers may be effected by securing the end fingers or coils to the clamping-bar. The connection of the end fingers to the bar may be effected in many ways—as, for example,

by forming eyes 9 in the bar adjacent to the hooks 5 and passing the ends of the coils through such eyes, the ends of the coils being held from withdrawal from the eyes by 5 enlarging the projecting ends, or by securing balls 8 thereon, as shown in Figs. 6 and 7, or the coils and the clamping-bar may be formed from a single piece of wire, as shown in Figs. 8 and 9. In such construction the 10 end portions of the coils and bar which form the hook 5 may be twisted together, as shown to the right in Fig. 8, or they may be bound together by the sleeve 10, forming a part of the flap or handle 11, as shown to the left in 15 Fig. 8. The flap affords a convenient handle for the withdrawal of the hook from the recess 6. A desirable means for securing the ends of the coil to the clamping-bar is shown in Fig. 10, and consists of a ball 8^a, having 20 slots or perforations at right angles to each other for the reception of the clamping-bar and at the ends of the coil. These parts are firmly secured in position by closing the walls or grooves against the wires.

25 As shown in Figs. 6 to 9, the bracing-ribs 7 may, when desired, be used for limiting the lateral movements of the intermediate fingers in connection with that construction in which the end fingers are attached to the clamping- 30 bar.

I claim herein as my invention—

1. In a pen-rack, the combination of a series of coils, a base provided with one or more transverse ribs for limiting the lateral movement of the coils, and a clamping-bar extending through the coils and having its ends connected to the base, substantially as set forth.

2. In a pen-rack, the combination of a series 40 of coils, a supporting-base, means for holding the coils spread or distributed along the base, and a clamping-bar passing through the coils and connected to the base, substantially as set forth.

3. In a pen-rack the combination of a series 45 of coils, a supporting-base, and a clamping-bar extending through the fingers or coils and connected to the end coils and constructed to be secured to the base, substantially as set forth.

4. In a pen-rack, the combination of a series of coils, a base or support having transverse ribs intermediate of the ends, and a clamping-bar provided at its ends with hooks adapted to engage the supporting-base, substantially 55 as set forth.

5. In a pen-rack, the combination of a series of coils, a base or support, and a clamping-bar extending through the coils and having its ends connected to the base, the ends of 60 the coils being provided with knobs or enlargements adapted to engage the clamping-bar, substantially as set forth.

6. In a pen-rack, the combination of a base provided with recesses, a series of coils arranged on the base, a clamping-bar provided with hooks adapted to engage the recesses in the base, and a sleeve provided with a flap or handle surrounding the hook, substantially as set forth.

7. In a pen-rack, the combination of a base, a series of coils arranged on the base, and a resilient clamping-bar provided with hooks adapted to engage recesses in the base, substantially as set forth.

8. In a pen-rack, the combination of a base, a series of coils arranged on the base, a clamping-bar and hooks having resilient connection to the clamping-bar, and adapted to engage recesses in the base, substantially as set forth.

In testimony whereof I have hereunto set my hand.

JAMES ADAIR.
